UNITED STATES PATENT OFFICE.

JOHN WOODBURY FULLER, OF DALTON, MASSACHUSETTS.

DESIGN FOR AN OUTER SOLE.

SPECIFICATION forming part of Design No. 31,294, dated July 25, 1899.

Application filed June 7, 1899. Serial No. 719,719. Term of patent 14 years.

To all whom it may concern:

Be it known that I, JOHN WOODBURY FULLER, a citizen of the United States, and a resident of Dalton, in the county of Berkshire and State of Massachusetts, have invented and produced a new and original Design for an Outer Sole, of which the following is a specification.

In the drawings, Figure 1 represents in plan 10 view an outer sole, illustrating my design; and Fig. 2 shows the said outer sole in edge view.

The leading feature of my design for an outer sole consists in a sole presenting at its opposite sides, starting from one end, divergent side lines, each prolonged and shaped to present convexed lines and then concaved lines to a point where the sole presents its narrowest part, and thereafter said lines are again diverged toward the opposite end of the sole, and from said narrowest line and between said narrowest line and the end of the sole there is a line of depression, which is shown best in Fig. 2.

The outer sole presents, (see Fig. 1,) start-

ing from one end, divergent side lines a b , 25 each prolonged and shaped to present convexed lines a' b' , then concaved lines a^2 b^2 to a point c , where the sole presents its narrowest part, and thereafter the lines a^4 b^4 are again diverged toward the opposite end of the 30 sole, and from the narrowest line and between said narrowest line and the end of the sole there is a line of depression d . (Best shown in Fig. 2.) Joining the divergent lines a b at each end of the sole there are straight cross-lines, which are each parallel to the line of depression d .

Having fully described my design, what I claim is—

The design for an outer sole, substantially 40 as shown and described.

In testimony whereof I have signed my name to this specification in the presence of two subscribing witnesses.

JOHN WOODBURY FULLER.

Witnesses:

R. C. PIERCE,
E. A. HALLE.
